- (57) **CLAIM**
An ornamental design for a modular food containment system, as shown and described in the accompanying drawings.

DESCRIPTION

A portion of the disclosure document contains material which is subject to copyright protection. The copyright owner has no objection to the facsimile reproduction by anyone of the patent document or the patent disclosure as it appears in the United States Patent and Trademark Office patent file or records, but otherwise reserves all copyrights whatsoever.

FIG. 1 is a perspective view of a modular food containment system, showing a tray with an integrally-formed chopstick stand, having two food accommodation portions, one drink accommodation portion, and a napkin accommodation portion showing my new design;

FIG. 2 is a front view thereof;

FIG. 3 is a back view thereof;

FIG. 4 is a side view thereof;

FIG. 5 is an opposite side view thereof;

FIG. 6 is a top view thereof;

FIG. 7 is a bottom view thereof;

FIG. 8 is a top perspective view of a plurality of stacked modular food containers;

FIG. 9 is a front view of a plurality of stacked modular food containers;

FIG. 10 is a perspective view of a second embodiment of a modular food containment system, showing a tray with an integrally-formed chopstick stand, having two food accommodation portions, one drink accommodation portion, and a napkin accommodation portion showing my new design;

FIG. 11 is an exploded perspective view of a plurality of modular food containers;

FIG. 12 is a front view thereof;

FIG. 13 is a back view thereof;

FIG. 14 is a side view thereof;

FIG. 15 is an opposite side view thereof;

FIG. 16 is a top view thereof;

FIG. 17 is a bottom view thereof; and,

FIG. 18 is a perspective view of a modular food containment system shown in use condition with the broken line showing of chopsticks, food containers, drink, and napkin forming no part of the claimed design.

The broken line showing of additional articles in FIGS. 8, 9, 10, and 11 is included for the purpose of illustrating environmental use and forms no part of the claimed design.
